TELEPHONE LOCK DEVICE

Charles V. Richey, Jamaica, N. Y.

Application June 22, 1939, Serial No. 280,633

2 Claims. (Cl. 179—189)

This invention relates to telephone lock device and more particularly to a device which may be readily attached to or detached from the dial of an automatic telephone.

5 It is a common practice to have telephones listed under the names of particular individuals which are answered by some other person, particularly in the absence of the person in whose name the phone may be listed. In such use, it 10 is desirable to receive incoming calls, but there is no reason for using the phone for the purpose of sending outgoing calls. In order to allow the phone to be used in this manner, it may be necessary to lock the dial against use.

15 One object of this invention is to provide a locking means adapted for use in connection with automatic dial telephones. Another object is to provide a locking device which can be applied to a dial telephone without requiring any reorganization or change in the standard equipment of the phone. Another object is to provide a relatively inexpensive device of the type described.

Other objects and advantages of this invention will appear from the following description taken 25 in connection with the accompanying drawing.

In the drawing wherein like reference characters indicate corresponding parts in the various figures—

Figure 1 is a side elevation of a dial telephone 30 device having assembled therewith a locking device incorporating features of this invention;

Figure 2 presents an enlarged partial plan view showing the device assembled with respect to the dial;

35 Figure 3 shows a longitudinal cross section of the dial and locking means substantially along the line 3—3 of Figure 2;

Figure 4 is an enlarged transverse cross section of the locking means taken substantially along 40 the line 4—4 of Figure 2;

Figure 5 is a horizontal partial cross section of the latch barrel of the device.

Considering the drawing in greater detail, the invention is shown in a preferred form, particularly in Figure 1, as applied to a dial type phone of the so-called French or foreign type in which the mouthpiece and receiver are combined in one structure. The base 10 has mounted thereon the switch compartment 12 upon which is rotatably mounted the dial element 14 having a plurality of finger openings 16 adapted for use in manually dialing a number. The usual card carrying member 18 which contains the telephone number or other appropriate data is snapped upon the upper 55 surface or face of the dial. The customary finger

stop 20 is secured at 22 through one flange 24 thereof to the switch housing 12 and has a horizontally extending arm 26 serving specifically as the finger stop portion per se of the device. In normal use, the person using the phone places 5 a finger in one of the openings 16 and moves the dial 14 in a clockwise direction until the finger strikes the finger stop 20 at which time the dial is released and returns to its normal position.

The locking means indicated generally at 28 10 includes relatively movable parts. A plate member 30 is provided with a downwardly turned arcuate flange 32 which is arranged to slip through one of the openings 16, more particularly the end or last opening 34 and to engage the dial 15 disc 14 as clearly observed in Figure 3. The outer extremity of this plate comprises an angularly extending portion 36 which is substantially flat and rectangular in transverse section, as seen in Figure 4. A downwardly extending pin 38 is 20 formed integral with or secured to the plate and extends downwardly therefrom in the same general direction as does the flange 32.

The other part of the locking device comprises 25 an outer barrel 40 having a latching or lock cylinder 42 rotatably mounted therein. This device insofar as the relative movement between the barrel and its cylinder may be very simple with the barrel being peened over as at 44 and 46 to 30 hold the cylinder within the longitudinal limits of the barrel.

The barrel is provided with a rectangular slot 48 extending part way through the barrel as readily seen in Figures 2 and 3. The vertical slot 35 50 connects with the horizontal slot and is arranged so as to provide a passage for the pin 38 when the plate and latching elements are being assembled together.

The cylinder 42 as more readily seen in Figure 40 5 is provided with a longitudinally extending slot 52 which latter extends part way along the outer surface of the cylinder. It then extends about the transverse periphery of the cylinder as clearly seen at 54 in Figure 5. The cylinder is provided 45 with a key slot 56 so that the cylinder can be rotated on its axis within the barrel to lock the plate and pin therein or for rotation in the opposite direction to press the slots 52 and 50 in alignment so that the pin may be removed from the 50 latching device.

The barrel is also provided with a slot 58 which extends transversely of the barrel and which is preferably positioned between the slot 48 and the cylinder 42. This latter slot is arranged to receive 55

the outer periphery of the dial disc 14 as may be observed in Figure 3.

- When it is desired to lock a dial phone against use, the plate member 39 is released from the lock combination and is moved under the finger stop 26 and tilted slightly so that the flange 32, which latter is less than 180°, may then be inserted in the opening 34 and caught about the edge of the latter. The barrel is then brought 5 into position so that the part 36 rides in the slot 48 with the pin 38 moving through the combined slot 50 and 52. At the time the pin 38 reaches the inner end of its movement, the periphery of disc 14 will be engaged or gripped within the 10 transverse slot 58. At such time the key in the key slot 56 can be turned thereby partly rotating the cylinder 42 and locking the pin 38 against longitudinal movement with respect to the barrel. With the parts in the position described the plate 15 cannot be withdrawn from the finger hole 34 because the disc 14 is firmly gripped by the barrel and consequently the plate cannot be tilted to release the flange 32. Furthermore, with the device in the position shown, the finger stop 26 20 prevents the plate from being raised and the disc itself prevents it from being lowered. Since the dial of the phone itself is locked against counter clockwise rotation the parts cannot be moved out from under the finger stop.
- 25 Although a preferred embodiment of this invention is illustrated and described, variations within the true spirit and scope of the same are to be determined by the appended claims.

What I claim is:

1. A telephone latching structure comprising a plate having an arcuate flange at one end to pivotally secure the plate in engagement with the finger hole of a telephone dial with the other end 5 of the plate angularly disposed with respect to the main body of the plate so as to extend beyond the edge of a telephone dial and having at its outer end a vertically disposed pin, and a latching barrel comprising an inner cylinder relatively rotatable and an outer portion containing a slot adapted to receive the pin and end portion of the plate and a second slot to engage the periphery of the dial, the wall of the inner rotatable cylinder being grooved longitudinally to receive 10 the pin for longitudinal movement of the cylinder and being angularly disposed during a portion of its extent to receive the pin and thus to prevent longitudinal movement of the inner barrel.

2. A locking device for dial telephones having 20 a dial and a fixed finger stop, comprising a plate having an arcuate flange at one end adapted to engage the wall of a finger hole of the dial, said plate being rotatable about said flange connection with the dial as a pivot and movable under 25 the fixed stop, means slidable on the other end of the plate and arranged to engage the periphery of the dial and to constitute an abutment engaging said finger stop, and locking means for securing the sliding means on the plate.

CHARLES V. RICHEY.
